CLAIM

The ornamental design for a thermometer, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view from the top and right side of the thermometer;

FIG. 2 is a back perspective view from the top and left side of the thermometer;

FIG. 3 is a front view of the thermometer;

FIG. 4 is a left side view of the thermometer;

FIG. 5 is a right side view of the thermometer;

FIG. 6 is a top view of the thermometer;

FIG. 7 is a bottom view of the thermometer;

FIG. 8 is a back view of the thermometer;

FIG. 9 is a front perspective view from the top and right side of the thermometer;

FIG. 10 is a back perspective view from the top and left side of the thermometer;

FIG. 11 is a front view of the thermometer;

FIG. 12 is a left side view of the thermometer;

FIG. 13 is a right side view of the thermometer;

FIG. 14 is a top view of the thermometer;

FIG. 15 is a bottom view of the thermometer;

FIG. 16 is a back view of the thermometer;

FIG. 17 is a front perspective view from the right side of the thermometer;

FIG. 18 is a back perspective view from the top and left side of the thermometer;

FIG. 19 is a front view of the thermometer;

FIG. 20 is a left side view of the thermometer;

FIG. 21 is a right side view of the thermometer;

FIG. 22 is a top view of the thermometer;

FIG. 23 is a bottom view of the thermometer; and,

FIG. 24 is a bottom view of the thermometer.
